UNITED STATES PATENT OFFICE.

JAMES L. BREESE, JR., OF CHICAGO, ILLINOIS, ASSIGNEE TO OIL DEVICES CORPORATION, OF CHICAGO, ILLINOIS, A CORPORATION OF ILLINOIS.

MEANS FOR REMOVING SOOT.

Application filed November 26, 1923. Serial No. 676,960.

The invention relates to means for removing soot and is dealt with in connection with boilers, although the invention is not limited to this particular application.

5 It is an object of the invention to provide new means for efficiently and speedily removing the soot from boiler surfaces to which it adheres.

10 A further object of the invention is to provide a novel method of soot or carbon removal from the interior surfaces of boilers.

15 The invention also comprises a number of other objects which will be readily apparent from a perusal of the description of the invention.

20 To the accomplishment of the objects stated and others which will appear hereinafter, the invention comprises the method of and the means for removing soot from boiler surfaces described in the following specification, particularly pointed out in the claims forming a part thereof, and illustrated in the drawing, in which,

25 Figure 1 is a sectional elevation of an oil burning boiler to which my invention has been applied.

Figure 2 is a front view of the boiler.

Figure 3 is a rear view of the boiler.

30 Figure 4 is a longitudinal section and elevation of the boiler, the section being taken along the line 4—4 of Figure 1.

Figure 5 is an enlarged detail view.

Figure 6 is a detail section on the line 6—6 of Figure 1.

35 Figure 7 is a detail section on line 7—7 of Figure 1.

Figure 8 is a part section, part elevation of a round boiler equipped with my invention, and

40 Figure 9 is a development of a section taken on the line 9—9 of Figure 8.

Referring to Figures 1 to 7 inclusive, the boiler generally designated by 10 comprises a plurality of hollow sections 11 which have the general outline of a triangle but with rounded corners. Each section comprises an inner wall plate 12 which at one edge is provided with a tongue 13 and at the other end is formed with a groove 14 so that the 45 tongue of one plate extends into the groove of the next plate and thereby insures a hermetic fit. Opposite the inner wall is an outer wall 15 having synclinal panels 16 and 17.

The inner and the outer walls 12 and 15 are connected by side walls 18 and 19 which 55 are formed with raised configurations 20, as will readily appear from Figure 1. The interior of each section constitutes a passage for water which is heated by the flame produced by a burner positioned in the center 60 of the boiler, but omitted from the drawing.

The inner wall 12 towards the lower end is bent inwardly as at 21 and then descends vertically to join the bottom 22 having a plurality of legs 23 to clear the floor. The 65 inner wall 12 extends at both sides beyond the side walls 18 and 19 and these protruding portions stop at a point slightly above the center of the boiler whereby the interspaces 24 between adjoining sections have 70 communication with the interior of the boiler affording thereby a passage for the hot combustion gases which at the top of the boiler divide and flow downwardly through the spaces 24 and through openings 25 enter the 75 flues 26. The sections 11 communicate with water heaters 27, 28 and 29, respectively, arranged at the bottom and top of the boiler and constitute chambers for water which ascends as it is heated by the downwardly 80 flowing hot gases.

The sections 11 are held together by tie rods 30 which are provided at the top and lower corners of the boiler structure. The upper rod extends through lugs 31 formed 85 on the end and center sections while the lower rods extend through bores 32 provided in the sections.

As appears from Figure 4, a plurality of sections whose numbers may vary are provided with end members 33 which contain the water chambers 34. The front end plate has an opening 35 closable by a hinged door 36 and underneath is a sliding door 37 movable between horizontal guide rails 38. To both sides of the sliding door are hand holes closed by doors 39. The flue passages 26 communicate through apertures 40 with a flue drum 41 from the center of which leads a riser pipe 42. In order to induce a draft, especially upon starting the boiler, an opening 43 is provided in the rear end plate 44 by means of which connection is established with the riser 42 and thus a draft induced in the upper part of the boiler.

In order to remove the soot adhering to

the surfaces of the interspaces 24, a pipe 45 may be provided at the upper end of the boiler, connected with a suitable source of water supply. Within each section 11 a 5 casting 46 is arranged, which has a longitudinal bore 47 terminating at the inner end in a transverse bore 48 opening into the interspaces 24 between adjacent sections 11. The connection between the bore 47 and the 10 pipe 45 is provided by a branch pipe 49 which is joined to the pipe 45 by a T-fitting 50. Inasmuch as the water pipe 45 is connected with the various interspaces 24 between the sections 11, it is clear that water 15 can be discharged into such interspaces to flush the surfaces thereof.

To prevent the water from reaching the interior of the boiler, baffle plates 62 are provided, which deflect the water.

20 The water passing thru the spaces 24 can be drained at the bottom of the flue passages 26 in any appropriate or preferred manner and as this feature is obvious, no illustration thereof is shown in the drawing.

25 In Figures 8 and 9 a modified construction of a boiler is shown, comprising a plurality of superposed generally annular sections 51 held together by bolts 52. The bottom section has a sliding door 53 and the section 30 immediately above the bottom section a door 54. The remaining sections of the boiler have no outer openings whatever. Each section contains a water chamber 55 and the various sections are inter-connected 35 by vertical passages 56 arranged, however, in staggered relation, as will readily appear by reference to the developed sectional view shown in Figure 9. In order to provide means for cleaning the surfaces of the passages 56 on which soot deposits, the horizontal pipe 57 extends into the upper section 51 and terminates in the annular depression 58 surrounding the upper end of the passage 56. Water may be introduced thru the pipe 45 and after the water fills the annular groove 58 it overflows said groove and passes thru an appertaining flue 56 and thence thru the subjacent flues 56 to collect in the chamber 59 whence the water is drained 50 thru a valve controlled pipe 60. The purpose of conducting streams of water thru the various flues 56 is, of course, identical with the purpose aimed at in removing the soot from the interspaces 24 of the first described modification.

If desired, the cleaning of the flues 56 may be effected by introducing water thru the pipe 60, sufficient quantities of water being introduced to circulate an upwardly 60 flowing stream thru the various flues 56. After the water fills the various passages 56 and reaches the highest point, a three-way valve 61 in the pipe 60 is turned so that the water and the soot carried by the water may 65 drain through a pipe 63. A quantity of the

soot will collect at the bottom of chamber 59 and a hand hole 64 affords access to said chamber to permit removal of the soot.

The use and operation of my invention are as follows:

It is a well known fact that boiler efficiency is largely reduced by the deposit or layer of soot or carbon which forms on the flue surfaces and which therefore reduces the absorption of heat from the gases of combustion by the heating medium, water, steam, vapor or air, which is employed in the particular heating system in question. The layer of soot or carbon forms an extremely efficient insulant and correspondingly reduces the efficiency of the heating plant as the thickness of the carbon layer increases.

I have found that a quick and efficient way of removing this surface layer of carbon is to strip or float it off by applying water to the carbon covered surface. I may trickle this water across the surfaces to be cleaned, or I may fill the flue passages with water, or I may spray water upon the flue 85 surfaces. The principle of the method, however, is the removal of the carbon not by the impact of the water but by the effect the water has of stripping or floating the carbon from the surface.

A peculiar advantage of my method, and of my apparatus, rests in the fact that it is easy to introduce water into the spaces and across the surfaces to be cleaned, even though the conformation of the flues may be intricate, whereas it is extremely difficult to obtain access to the passages for brushing or for scraping or for blowing out the carbon. Since I employ not so much the impact of the water as the stripping or 105 floating effect which the water has, I do not need actually to squirt or spray the water directly against a given surface. It is sufficient if, whether by direct spraying or by the downward flowing of the water or spray 110 or by the rise in level of the water introduced into the flue passages, the various soot or carbon covered surfaces are all exposed to the stripping or floating action of the water.

115 Since my method and apparatus largely eliminate the necessity of having easy access to the interior passages of the furnace, I am able very substantially to simplify my furnace design and largely to eliminate exterior openings, special doors, hand holes and the like, these openings being reduced to a minimum in both number and size.

I have illustrated the application of my invention to two different types of boiler 125 but it will be realized, of course, that I do not wish to limit myself to the use of my invention with these specific types of boiler or with any specific boiler types, since my inventive idea is capable of a general appli- 130

cation independent of minor or even of very considerable changes in design of the particular furnace or boiler to which it is applied.

5. In the main it consists of providing any suitable boiler or furnace with the necessary water connections, or the apertures for inserting water connections, whereby water may be poured or sprayed or introduced in
- 10 any suitable manner into the flue passages. In order to maintain a circuit of fluid circulation and to avoid the flooding of the main combustion chamber I may employ the structure shown in Figure 1 which includes
- 15 the water pipes 45, a plurality of inlets from said supply pipes to the various flue sections, deflector veins 62 to prevent the passage of the water into the central combustion chamber, and run off passages of
- 20 any suitable type for the withdrawal of the water from the bottom of the flue passages.

In applying the same invention to the form of furnace or boiler shown in Figures 8 and 9 I admit the water through the pipe 57 and withdraw it through the pipe 60. Obviously I might reverse the flow of the water, admitting it through the pipe 60 and withdrawing it through the pipe 57. The pipe 57 being lower than the edge of the uppermost of the annular boiler sections, will drain the water before it can ever flow into and flood the central combustion chamber.

Obviously my method may be practiced independently of the structures herein shown, for example independent of any fixed or permanent piping connection. For example if the members shown in Figure 6 were removed, water could be manually poured into the boiler of Figure 1 or could be introduced by means of any suitable pipe or hose.

I claim:

1. In a boiler including a combustion

chamber and flue passages downwardly extending from the upper portion thereof, means for cleaning the interior walls of said flue passages, comprising means for flowing water across said surfaces, and means for clearing from said passages the water so admitted, and means for excluding the water so admitted from access to the combustion chamber.

2. In a boiler including a centrally disposed combustion chamber and a plurality of circumferentially disposed revertible flue passages, a water connection for the upper portion of the flue system and a water connection for the lower portion of said flue system, said connections constituting means for inducing a flow of water through the flue system.

3. In a boiler including a combustion chamber and flue passages downwardly extending from the upper portion thereof, means for cleaning the interior wall of said flue passages comprising means for causing a flow of water downwardly through said passages and along said walls, and means, associated with the passages between combustion chamber and flues, for preventing the access of water from the flues to the combustion chamber.

4. In a boiler including a combustion chamber and flue passages downwardly extending from the upper portion thereof, means for cleaning the interior walls of said flue passages comprising means for causing a flow of water downwardly through said passages and along said walls, and means, associated with the passages between combustion chamber and flues, for preventing the access of water from the flues to the combustion chamber, comprising overhanging flanges downwardly and outwardly projecting thereover.

In witness whereof I affix my signature.

JAMES L. BREESE, JR.
